UNITED STATES PATENT OFFICE.

JOHN N. WALLIS AND THEODORE WALLIS, OF FLEMING, NEW YORK.

IMPROVEMENT IN GLASS COFFINS.

Specification forming part of Letters Patent No. **139,095**, dated May 20, 1873; application filed April 12, 1873.

To all whom it may concern:

Be it known that we, JOHN N. WALLIS and THEODORE WALLIS, of Fleming, in the county of Cayuga and State of New York, have invented a new and Improved Glass Casket, of which the following is a specification:

In the accompanying drawing—

Figure 1 represents a top view of our improved glass casket, and Fig. 2 a vertical transverse section of the same on the line *c c*, Fig. 1.

Similar letters of reference indicate corresponding parts.

The object of our invention is to construct a glass casket which contains sufficient strength, with an easy replacing of the different parts, to be hermetically cemented together. Our invention pertains to an improved construction of glass caskets; and consists in providing the sides with clasps and rims or flanges whereby they are conveniently and securely locked together.

In the drawing, *A* represents the side pieces; *B*, the top; and *C*, the bottom pieces of the casket, molded suitably of glass. The side pieces *A* are wider at the head end than at the foot end, having straight sides and conical ends, tapering downward from top to bottom. Projecting rims *a* run along the upper

edge pieces *A*, which support the top piece *C*. Grooves *b*, along the bottom edge, opening toward the head end, serve for the bottom *C* to slide in. One of the side pieces *A* is provided with projecting flanges or rims *d*, which run up vertically at head and foot ends, and fit into correspondingly-grooved clasps *e*, producing a firm connection of the side pieces *A*; at the same time, it is a connection easily and readily made, is not easily broken, and does not materially impair the ornamental appearance of the casket. Top part *B* is beveled along the edges, to be hermetically sealed to rims *a*; and the bottom and side parts are similarly sealed by some suitable cement, forming a strong and rigidly-cemented casket.

Having thus described our invention, we claim as new and desire to secure by Letters-Patent—

In a burial-casket, the sides *A A*, provided with the vertical flanges *d* and clasps *e*, respectively, interlocking, as shown and described.

JOHN N. WALLIS.
THEODORE WALLIS.
